CURTAIN STRETCHER AND SUPPORT THEREFOR

Filed Feb. 5, 1949

ATTORNEYS.

UNITED STATES PATENT OFFICE

2,630,652

CURTAIN STRETCHER AND SUPPORT
THEREFOR

Dora G. Amado, Long Beach, N. Y.

Application February 5, 1949, Serial No. 74,777

8 Claims. (Cl. 45—24)

1

This invention relates to curtain stretchers, and more particularly to a curtain stretcher of the pinless type.

The present application is a continuation in part of my co-pending application Ser. No. 754,305, filed June 12, 1947, now abandoned.

It is the primary object of the present invention to provide a stretcher which is more quickly applied to a curtain, requires for its application to a curtain less skill, and stretches a curtain more uniformly, than the well-known pin-type curtain stretchers.

It is another important object of the present invention to provide a stretcher which, in contrast to the pin-type curtain stretchers, is not liable to tear a curtain being stretched.

The above and other objects, features and advantages of the present invention will be more fully understood from the following description considered in connection with the accompanying illustrative drawings.

In the drawings:

Fig. 1 shows a curtain mounted on a stretcher which embodies the present invention;

Fig. 2 shows a few of the disconnected elements of the stretcher at a larger scale than in Fig. 1;

Fig. 3 shows an enlarged corner of a type of curtain which may be mounted on the instant stretcher;

Fig. 4 is a section taken on the line 4—4 of Fig. 3;

Fig. 5 shows a curtain mounted on a stretcher which embodies the present invention in a modified manner;

Fig. 6 shows the disconnected elements of the modified stretcher at a larger scale than in Fig. 5;

Fig. 7 is a perspective view of a frame on which either curtain stretcher may be mounted; and

Figs. 8 and 9 are enlarged fragmentary sections taken on the lines 8—8 and 9—9, respectively, of Fig. 7.

Referring to Fig. 1, the reference numeral 10 designates a curtain stretcher which comprises a plurality of readily connectible and disconnectible parts that are applied to a curtain 12.

An example of a curtain suitable for mounting on the instant stretcher 10 is illustrated in Figs. 1, 3 and 4. Thus, the curtain 12 may be provided with an endless pocket 14 along the margins thereof, the pocket being conveniently formed by folding back the outer margins of the body 16 of the curtain and sewing them to the latter as at 18. In order to gain access to the endless pocket 14 in the curtain 12, the stitching 18 may conveniently be interrupted at one or more of the

2

curtain corners to provide passages 20 through which to introduce the separate parts of the curtain stretcher 10 into the pocket.

The curtain stretcher 10 comprises, in the present instance, four preferably identical corner pieces 22 which may be the elbow shape shown in Fig. 2. The corner pieces 22, which may be made of any suitable, preferably round material, such as wood or plastic, for instance, are provided with holes or sockets 24 for the reception of the ends of rods 26 that may be made of any suitable bar stock, such as wood or plastic. In the present instance, there are provided four of these rods 26 which, in the assembled state of the stretcher, are interposed between the corner pieces 22 in the manner shown in Fig. 1.

The disassembled parts 22 and 26 of the stretcher are inserted into the endless pocket 14 in the curtain 12 through the passages 20 thereof, in such order that they are, on their successive insertion, in position for ready connection with each other. The curtain 12, which is usually made of more or less stretchable material, such as lace, is thereupon stretched, longitudinally as well as laterally, sufficiently to permit the insertion of the ends of the rods 26 into the confronting sockets 24 in the adjacent corner pieces 22. Thus, all of the several disassembled parts 22 and 26 of the stretcher may first be inserted into the endless pocket 14 in the curtain and subsequently connected with each other, their connection requiring momentary stretching of the curtain beyond the extent to which the same will be stretched by the assembled stretcher 10.

Another, and perhaps preferred, way to apply the present stretcher to the curtain 12 is to insert the corner pieces 22 and rods 26 into the endless corner pocket 14, in such order that they may directly be connected with each other on their insertion into the pocket 14. The disassembly of the assembled stretcher 10 and the removal of the parts 22 and 26 thereof from the endless pocket 14 in the curtain is fully obvious from the preceding description.

While the present stretcher 10 may be applied to a curtain having a continuous pocket, as described, it is obvious that the stretcher may with equal advantage be applied to curtains having pockets interrupted at the corners, or to curtains having two opposed pockets along the top and bottom, for instance. Also, in order to accommodate curtains of varying sizes, the instant stretcher may be provided with interchangeable rods 26 of different lengths.

Fig. 5 shows a modified stretcher 10' applied

to a curtain 12' which may in all respects be like the curtain shown in Figs. 1 and 3. The modified stretcher 10', which also comprises separate connectible and disconnectible parts, is distinguished from the earlier described stretcher 10 by requiring considerably fewer parts than the latter. Thus, the modified stretcher 10' omits the separate corner pieces of the stretcher 10, and instead combines each corner piece with a rod as an integral part. The modified stretcher 10' consists, in the present instance, of four parts 30, 30', 32 and 32', of which the parts 30 and 30' and the parts 32 and 32' form identical pairs, respectively. The parts 30, 30' and 32, 32' may be made from any suitable bar stock, such as wood or plastic, and each of these parts is of the general L shape shown in Figs. 5 and 6, so as to include a corner of the stretcher 10' in its assembled form.

For the application of the stretcher 10', the disassembled parts 30, 30' and 32, 32' are inserted in any suitable order into the endless curtain pocket 14 through the passages 20 thereof, so that each inserted part will form a corner of the stretcher to be assembled. The curtain is, on the insertion of the stretcher parts in the pocket 14 therein, sufficiently stretched, longitudinally as well as laterally, in order to bring the confronting end surfaces of the adjacent stretcher parts into abutting engagement with each other (Fig. 5). In the present instance, it is this end-to-end abutting engagement of the stretcher parts which is solely relied on to hold the stretcher in its assembled condition in the stretched curtain. It is, therefore, desirable that the cross-sectional area of the bar stock selected for the stretcher parts is such that the latter are prevented by the surrounding curtain pocket 14 from becoming laterally displaced from their abutting end-to-end engagement.

The instant curtain stretcher 10' lends itself most readily to adjustment to different sizes, by merely interposing bar inserts (not shown) between the adjacent end surfaces of the parts of the stretcher. Thus, the instant stretcher 10' may be provided with bar inserts of different lengths in order to render the stretcher applicable to curtains of varying sizes. The bar inserts, which are preferably made from the same bar stock as, the stretcher parts 30, 30', 32 and 32', will safely be held in abutting end-to-end engagement with the adjacent stretcher parts between which they are interposed, by the curtain pocket 14 which as above explained, prevents lateral displacement of the stretcher parts 30, 30', 32 and 32' wherever they are in direct end-to-end abutting engagement.

Fig. 7 shows a frame 40 for supporting either curtain stretcher 10 or 10'. In the present instance, the frame 40 is shown supporting the modified stretcher 10' with a curtain thereon. The frame 40 comprises front and rear legs 42 and 44, respectively, which are suitably secured to a frame-like stretcher support 46. The legs 42 and 44 may be reinforced by transverse braces 48. The support 46 of the frame 40 is preferably provided in its front face 50 with a continuous groove 52 (see also Figs. 8 and 9) for the reception of the stretcher 10' and curtain 12 thereon in located position on the frame 40. The stretcher 10' and curtain thereon may conveniently be held in correctly located position on the support 46 of the frame 40 by simple spring clamps 60, for instance, which may readily be

sprung over the support 46 and located stretcher thereon in the manner shown in Figs. 7 and 8.

The frame 40 is equally adaptable for the support of the curtain stretcher 10 and curtain thereon, the corner pieces 22 of the stretcher being adapted for reception in the corresponding corners of the continuous groove 52 in the frame support 46, and the spring clamps 60 being similarly applied, as before, in order to hold the located stretcher 10 and curtain thereon on the frame support 46.

While I have shown and described the preferred embodiment of my invention, it will be understood that various changes may be made in the present invention without departing from the underlying idea or principles of the invention within the scope of the appended claims.

Having thus described my invention, what I claim and desire to secure by Letters Patent is:

1. A stretcher for a curtain having pockets along at least two opposite margins thereof, respectively, comprising rods extensible through the curtain pockets, respectively, and members removably interposable between the adjacent ends, respectively, of said rods for holding the latter spread apart in position to stretch the curtain, said members and rods having smooth unencumbered surfaces to facilitate the insertion thereof into the curtain pockets and to prevent damage to the latter.

2. A stretcher for a curtain having an endless pocket along the margins thereof, comprising separate bars having smooth uninterrupted peripheral surfaces and being insertable in the curtain pocket and having means for removably connecting them in said pocket in end-to-end relation with each other to form a rigid frame on which the curtain is stretched, the surfaces of said bars and connecting means being unencumbered to facilitate the insertion thereof into the curtain pocket and to prevent damage to the latter.

3. A stretcher for a curtain having an endless pocket along the margins thereof, comprising separate rigid rods insertable in the curtain pocket to extend along the margins, respectively, of the curtain, and separate connectors also insertable in the curtain pocket and having sockets releasably to receive the adjacent ends of said rods and form with the latter a rigid frame on which the curtain is stretched, said rods and connections having smooth unencumbered surfaces to facilitate the insertion thereof into the curtain pocket and to prevent damage to the latter.

4. A stretcher for a rectangular curtain having an endless pocket along the margins thereof, comprising separate rigid rods insertable in the curtain pocket to extend along the margins, respectively, of the curtain, and separate corner members also insertable in the curtain pocket and having rectangularly disposed sockets releasably to receive the adjacent ends of said rods and form with the latter a rigid rectangular frame on which the curtain is stretched, said rods and members having smooth unencumbered surfaces to facilitate the insertion thereof into the curtain pocket and to prevent damage to the latter.

5. A stretcher for a rectangular curtain having an endless pocket along the margins thereof, comprising separate rigid rods insertable in the curtain pocket to extend along the margins, respectively, of the curtain, and separate elbow-shaped corner members also insertable in the curtain pocket and having in their ends rectangularly disposed sockets releasably to receive the adja-

cent ends of said rods and form with the latter a rigid rectangular frame on which the curtain is stretched, said rods and members having smooth unencumbered surfaces to facilitate the insertion thereof into the curtain pocket and to prevent damage to the latter.

6. A stretcher for a quadri-lateral curtain having an endless pocket along the margins thereof, comprising four separate rods of L-shape having plane end faces and being insertable in said curtain pocket in such relation therein that the bend in the L of each rod occupies a corner of the curtain, said rods being of such lengths relative to the curtain that they stretch the latter longitudinally and laterally when the inserted rods are engaged with their adjacent end faces in abutting relation, said abutting face-to-face engagement of said rods solely holding the latter in their assembled relation in the curtain pocket.

7. A support for a curtain stretcher comprised of bars adapted to be inserted and connected in an endless marginal pocket of a curtain to be stretched, said support comprising a frame having a continuous groove in a face thereof in which removably to place the stretcher bars, and means on said frame for releasably clamping the stretcher bars in the groove in said frame.

8. A stretcher for a rectangular curtain having an endless pocket along the margins thereof, comprising separate rigid rods insertable in the cur-
